Primary Examiner — T Chase Nelson*Assistant Examiner* — Sydney Margaret Parsley(74) *Attorney, Agent, or Firm* — Brooks Kushman P.C.(57) **CLAIM**

The ornamental design for a mobile dwelling unit, as shown and described.

DESCRIPTION

FIG. 1 is a front isometric view of a mobile dwelling unit with front windows closed;

FIG. 2 is a left isometric view thereof;

FIG. 3 is a right isometric view thereof;

FIG. 4 is a top isometric view thereof;

FIG. 5 is a bottom isometric view thereof;

FIG. 6 is a back isometric view thereof;

FIG. 7 is a front isometric view of the mobile dwelling unit with front windows open;

FIG. 8 is a left isometric view thereof;

FIG. 9 is a right isometric view thereof; and,

FIG. 10 is a top isometric view thereof.

The broken lines show environmental structure and portions of the mobile dwelling unit that form no part of the claimed design.

1 Claim, 10 Drawing Sheets(56)
